UNITED STATES PATENT OFFICE.

FREDERICK H. ARNOLD, OF READING, PENNSYLVANIA.

DESIGN FOR A SAFETY-RAZOR.

No. 38,754.

Specification for Design.

Patented Aug. 20, 1907.

Application filed November 12, 1906. Serial No. 343,162. Term of patent 14 years.

To all whom it may concern:

Be it known that I, FREDERICK H. ARNOLD, a citizen of United States, residing at Reading, in the county of Berks and State of Pennsylvania, have invented and produced a new, original, and ornamental Design for Safety-Razors, of which the following is a specification, reference being had to the accompanying drawings, forming a part thereof. Figure 1 is a plan view, showing the ob-

verse side of my design. Fig. 2 is a plan view, showing the reverse side of my design.

I claim:

The ornamental design for a safety razor, as shown.

FREDERICK H. ARNOLD.
